CLAIM

The ornamental design for a coupling as shown and described.

DESCRIPTION

FIG. 1 is a perspective view of a coupling according to my new design.

FIG. 2 is a side view of the coupling; and,

FIG. 3 is an end view of the coupling.

The dashed broken lines in the drawing depict portions of the coupling that form no part of the claim. The dash-dot broken lines define the boundaries of the claim and form no part thereof.
